METHOD OF RECOVERING WELL FLUIDS

Jay P. Walker, Tulsa, Okla., assignor to Eureka
 Process Corporation, Tulsa, Okla., a corpora-
 tion of Delaware

Application February 18, 1939, Serial No. 257,046

7 Claims. (Cl. 62—175.5)

This invention relates to new and useful improvements in methods of recovering well fluids.

The invention has particularly to do with certain improvements upon the invention set forth in our Letters Patent No. 2,080,351, issued May 11, 1937, and upon the invention disclosed in our application for Letters Patent filed August 12, 1938, Serial No. 224,468.

As recited in the foregoing patent and application, the hydrocarbons which are processed occur in vaporous form, or in solution with the natural gas, usually only under high pressures within the pressure range of retrograde condensation, and at temperatures in excess of 100 degrees F. These are natural vapors, and so far as is known, have only been found in a native state or formation and in commercially recoverable quantities, since wells have been drilled into the deeper pools, usually deeper than four thousand feet.

These wells for want of a better term have been called, in the industry, "distillate" wells, probably because these gaseous vapors or fluids when converted or processed to a liquid phase, have some of the characteristics of common hydrocarbon distillates. These wells are also called "combination" wells because they may produce some liquids, although the well stream is predominantly gas or gaseous, frequently comprising up to 98 per cent methane or ethane gas. It has been found that by cooling or reducing the pressure, or by both cooling and pressure reduction of these vaporous or gaseous fluids, much more of the liquefiable content is condensed or recovered under high pressures, and the liquefiable fractions so condensed from wells are sometimes referred to as "condensates." It follows from the foregoing analysis that distillate wells apparently exist because of retrograde vaporization and when the pressure is reduced within certain limits, usually above 700 pounds, retrograde condensation will occur.

As practiced in our preceding inventions, the liquefiable fractions or components of these gaseous fluids have been converted to the liquid phase, and recovered as liquids, by admixing with the well stream a cold liquefaction liquid. The liquefaction liquid has preferably been obtained from the recovered native liquids and recirculated as a reflux or admixed with the well stream. The best results have been obtained by sufficiently cooling the reflux to cause condensation. We have coupled cooling with pressure reduction, but confining such pressure re-

duction substantially to the retrograde condensation range.

The particular pressure at which the retrograde condensation range begins is somewhat controlled by the composition of the liquids in solution with the natural gas. While some liquids may vaporize or go into solution with the gas at a pressure as low as 650 pounds, other liquids will not vaporize until a much higher pressure is reached. When handling one particular natural gas, the retrograde condensation range may begin at 650 or 700 pounds, while with another natural gas the retrograde range may not begin until 800 or 1,000 pounds, or even higher, are reached. At this time, it would be difficult to limit the maximum pressure of the retrograde condensation range. When processing, within such pressure range, cooling of the gas has much to do with the recovery of liquids.

As heretofore practiced, the liquefaction liquid has to a large extent been artificially cooled and while artificial or extraneous cooling is highly satisfactory, it is more or less expensive to produce as well as involving costly equipment.

One object of the invention is to provide an improved method wherein hydrocarbon liquids which are recovered by condensation or precipitation and agglomeration are cooled without the use of artificial or extraneous means; or wherein only a portion of the cooling is done with artificial or extraneous means, whereby economical cooling and improved recovery may be accomplished.

Another object of the invention is to provide a hydrocarbon liquid recovery method wherein a liquefaction liquid is provided which has been denuded of gas to such an extent as to make a more stable and efficient liquefaction liquid; or which liquid has been denuded of gas as well as certain of the more volatile or unstable hydrocarbons so as to provide a liquefaction liquid capable of absorbing greater quantities of liquefiable fractions and thus making for increased recovery of desirable hydrocarbon liquids.

An important object of the invention is to provide a method of the character described wherein the free water, flowing in the well stream, which water may be augmented by cooling and condensation, is extracted as a preliminary step; thus making for more efficient and economical recovery, as well as requiring a lesser quantity of dehydrating fluid to inhibit the well stream against the formation of gas hydrates.

One of the principal objects of the invention is to provide a method of the character described

wherein the well stream is preferably cooled or manipulated to condense or precipitate some of the heavier or higher boiling-point hydrocarbons, but particularly wherein the hydrocarbon liquids, flowing from the well and augmented by said condensates, are extracted for use as a liquefaction liquid as well as to quickly and economically recover them from the well stream.

A further object of the invention is to provide an improved method wherein the uncondensed or fixed gases, such as methane and ethane, and in some instances some of the lighter or more volatile hydrocarbons may be readily separated from the recovered liquids which contain miscible gases in solution, and such recovered liquids subjected to a sudden or rapid pressure reduction, whereby gas in solution is quickly flashed off, or so quickly released from solution, as to greatly reduce the temperature of the liquid; the degree of cooling depending upon the amplitude of the pressure reduction and pressure drop and the particular hydrocarbon composition of the liquid. The relatively small amount of gas flashed off, may usually be readily disposed of, as for fuel or lease purposes. One advantage of this method is that the gaseous well stream may be processed within the retrograde pressure range of condensation and the uncondensed or denuded fixed gases recovered at a high pressure within said range, so as to be returned to a sub-surface reservoir without expensive recompressing. The pressure of the recovered liquids may be reduced below the retrograde condensation range, well down into the low pressure range without effecting the preceding steps of the method.

A further object of the invention is to provide a method wherein the recovered liquids may be carried through a pressure reduction which will cool the liquids to a low degree, possibly as low as 20 degrees F. or lower, whereby a portion of the liquids may be delivered to the stock tanks substantially denuded of undesirable gases, thus producing a more stable product. The other portion of the recovered liquid may be utilized as a cold reflux. The pressure of this reflux is raised sufficiently to inject it into the well stream. The ratio of this injected cold reflux to the amount of native liquid recovered from the well stream, may run as high as 100 to 1, but these figures are subject to a wide range of variation, depending upon the hydrocarbon composition of the well stream and the recovered liquids.

Still another object of the invention is to provide a method wherein the gas in solution is flashed off or released from the recovered liquids to cool them, and a portion of such liquids is carried through a pump to build up the pressure sufficiently to recirculate it as a reflux, or wherein the reflux which has been cooled as described is carried through a further cooling step, either before or after pumping, whereby its temperature is lowered to a degree which may not be obtainable merely by pressure reduction. In the latter event the amount of artificial or extraneous cooling may be small, and in most instances will be when compared with methods wherein the entire cooling is done by artificial means.

An important object of the invention is to provide a method wherein a cold reflux medium is produced which has been denuded of the more volatile or lighter fractions, such as ethanes and methanes, and in some cases, even propanes and some butanes, by flashing liquids recovered from a high pressure gas separating step, from such

high pressure to such a low pressure as to release from solution, the more volatile or lighter fractions which when released change from a liquid phase to a gas or gaseous phase. Such a reflux medium will be so thoroughly denuded, as well as cooled, that when introduced into the flowing well stream, it becomes a much more efficient medium for absorbing or converting light or gaseous vapors into a solution phase, so as to be again flashed, thus making for continuous cooling.

Apparatuses designed for carrying out the method will be hereinafter described, together with other features of the method, and reference is made to the accompanying drawing as illustrating such apparatuses, and wherein:

Figure 1 is a diagrammatical view of an apparatus for carrying out the method where dehydrating is not used, and

Figure 2 is a diagrammatical view of another apparatus for carrying out the method.

In the drawing, the letter A designates a flowing well of the character described. These wells are found in various localities at depths, usually more than three thousand feet, many having a depth of 8,000 feet and deeper. The pressures in the sub-surface reservoirs may range from approximately 650 pounds per square inch to more than 4,000 pounds per square inch. Certain liquid constituents which at a lower pressure are found as liquids, apparently go into solution in the gas at higher pressures because of the high temperatures, as well as the high pressures. The lower limits of the pressure range of retrograde condensation, or the pressure at which such range begins, varies according to the composition of the hydrocarbons. Such pressure range has not been found below 650 pounds per square inch, but it may begin there or at 800 or 1,000 pounds, or even higher. The upper limits of such retrograde pressure range have not been definitely established.

The shut-in pressure of the well will be somewhat less than the reservoir pressure. The temperatures of the well fluids in the sub-surface reservoir and at the well head may vary from approximately 100 degrees F. to 185 degrees and higher, when flowing under high pressure from the well; such high pressures ranging from 1,000 pounds to 3,000 or 4,000 pounds and higher. All of these figures and measurements are subject to variation and are based upon data and information available at this time. Future developments may make marked changes and the invention is not to be limited by these figures and measurements. The method as herein set forth has operated successfully in the recovery of the particular hydrocarbons sought.

The well stream in flowing from the reservoir up the well bore or pipe to the well head, will as a rule undergo some physical changes. The heat exchange brought about by temperature reduction and contact with the progressively cooler well pipe and earth heat exchange will cause some of the products in vapor phase to be converted to a liquid phase, and this applies to water vapors as well as hydrocarbon vapors. Frequently, if not usually these vapors will be more or less composed of the heavier hydrocarbons. These condensates precipitated by heat exchange in the upstream flow in the well will continue to flow with the well stream as free water and free hydrocarbon liquids, so that when the stream discharges from the well the free liquids will be entrained or flowing with the gase-

ous stream. In the character of wells under treatment the amount of free liquids discharged from the well will usually be less than fifty per cent by volume of the total recoverable well stream liquids when under their maximum flowing pressure.

In the wells which could be profitably handled, under this method, it has been found that the total recovered liquid, by volume, has ranged from approximately one-half gallon to more than three gallons per thousand cubic feet of gas. The recovered liquids, after the unstable gases have been separated, are in some instances, marketable as low grade motor fuel, ranking as what is now known as "third grade gasoline."

The well stream is conducted through a pipe 10 (Figure 1) from the well. When the pressure is very high, as from 1,500 to 4,000 pounds per square inch, it may be desirable to reduce it to some extent, usually not below 1,200 to 1,500 pounds per square inch; and for this purpose a regulating valve or choke 11 is connected in the pipe 10. The valve 11 may be left wide open or it may be used to reduce the pressure. If the valve 11 is left wide open, the pressure may be reduced at a later step. Precooling of the well stream is often desirable and, for this purpose, we have shown a cooler B, which for economical reasons may be a water cooler. This cooler is connected in the pipe 10, so that the well stream flows through the same. This cooler may be omitted and no precooling performed.

Suitable means for extracting water or other dehydrating apparatus as a water knockout C, may be connected in the pipe 10 after the cooler B, as is shown in the drawing. The well stream as a rule, aside from its water content, will include fixed gases, such as ethane and methane, free hydrocarbon liquids which are of the same characteristics and components as the distillates or condensates to be recovered and constitute a part thereof, and gaseous vapors or fluids, all entrained in said stream.

The problem is not only to recover the liquefiable fractions from the vapor phase or gaseous fluids, but to stabilize the entrained hydrocarbon liquids so that they will not revert to the vapor phase and be carried off with the tail or residual gas after separation of the recovered liquids while under high working pressure. A pipe 12 leads from the knockout C to a container or tank D which we have called a "liquedenser," partly for want of a better name, and partly because the well stream is somewhat liquefied or condensed in passing through the tank. The liquedenser may have any suitable interior structure best designed for commingling the liquids and fluids of the stream.

The denuded liquefaction liquid is composed of hydrocarbons which have been recovered from the well stream and while it may not have exactly the same composition as the native distillate liquids or fractions to be recovered it will include hydrocarbon components of substantially the same composition as such liquids. If admixed with the gaseous well stream in quantities, which may be greatly in excess of the amounts inherent to the stream so that greater surficial contact and greater cooling thereby is effected, the affinity of like components will bring about an increased precipitation of like liquefiable fractions entrained in the well stream, in contrast to the probable recoveries where lesser

amounts of the liquefaction fluid are introduced, but under all conditions cooling, which results in condensation is important.

The denuded liquefaction fluid recovered and cooled as hereinafter described, may be admixed with the well stream at any suitable point. Up to the point of admixture the well stream may be referred to as such, but from this point it will be hereinafter designated in this description as the agglomerated stream, although it is in actuality the well stream with the reflux admixed therewith, and may be said to be in the state of condensing the liquefiable constituents or as preparing the same for condensing.

15 In Figure 1, the pipe 12 connects with a tank or liquedenser D, which as stated may have any suitable construction, however, it is desirable to provide some sort of admixing means, such as baffles 13, which will cause the liquefaction liquid and the well or gaseous stream to thoroughly admix. The liquefaction liquid may be introduced into the liquedenser or tank D through a pipe 14 which is connected to the pipe 12 in advance of a choke 15, which is also connected in the pipe 12 adjacent the tank D. The pipe 14 includes a cut-off valve 14'. It may be desirable to introduce the liquefaction liquid or reflux at some point between the well A and the liquedenser D and for this purpose a pipe 16 including a cut-off valve 17, is illustrated as extending from the pipe 14 to the pipe 10. Either of the pipes 14 or 16 may be omitted, or if one is to be used the cut-off valve therein is opened and the cut-off valve in the other pipe is closed. Of course, it will be necessary to build up the pressure of the reflux sufficiently to introduce it into the well stream.

Whether the pressure is reduced at the valve 11 or not the stream will reach the choke 15 at such a high pressure that a pressure reduction at this point will aid materially in reducing the temperature of the stream, particularly when the cold reflux is introduced. As an example the well may produce at 2,800 lbs. and the valve 11 may be adjusted to cut the pressure to 2,000 lbs., or it may not be reduced at this point. The choke may be set to reduce the pressure to 1,100 lbs. Such pressure reduction will result in cooling of the stream and condensing of liquefiable hydrocarbon constituents.

As has been pointed out, the primary well stream of these distillate type of wells is substantially composed of free gases not subject to appreciable liquefaction under high pressures and prevailingly high temperatures, as well as fractions in vaporous form which are liquefiable, and other fractions in the liquid phase. These components prevail in a state in which the vaporous and liquid phase fractions which have not been condensed are highly dispersed or atomized.

In the process of admixing, a major change in the character of the well stream fluids takes place in the form of an increased liquid content which results in a unification of the highly atomized or dispersed liquid particles in the primary well stream fluids with the more massive liquid particles of the liquefaction liquid. During this step, in which the unification of the more massive liquid particles takes place, the resultant liquid and gas admixture is prepared for separation of the more volatile gases, which is efficiently accomplished, due to the fact that

greater proportions of the highly dispersed liquefiable particles have united or combined with the more massive liquid particles of the medium. During the process of admixture the cooling of the fluids which will take place will further increase the recovery of liquefiable fractions from the combined fluids, due to the condensing which takes place.

The fluids enriched by the liquefaction liquid flow from the liquedenser D under reduced temperatures and high pressure which is usually above 650 pounds because the well stream is discharged at pressures within the range of retrograde condensation and unless reduced at the well head may flow at considerably more than 650 pounds and frequently above 1,000 pounds. The admixed stream flows from the liquedenser through a pipe 18 which may include a valve 19. The stream flowing through this pipe has a much greater liquid content or liquid-to-gas ratio than the well stream as it flows from the well. During this flow the hydrocarbon liquids and the liquefiable fractions which have been and are being precipitated or condensed will agglomerate as has been explained in our previous applications.

The flowing stream having been prepared for separation is conducted by the pipe 18 to a separator E wherein the components, liquids and gas, will readily yield to separation, the liquids descending to the lower portion and the gases rising. The pipe 18 may contain a valve 20 adjacent the separator and this valve may be either a hand valve or a regulating valve or a choke so that if it is desired to regulate the pressure of the stream entering the separator, such regulation may be accomplished, however, the valve 20 may be omitted entirely.

It is one of the theories of retrograde condensation, as hereinbefore explained, that reducing the pressure within the retrograde range causes precipitation of liquefiable constituents which are in a vapor phase. This is also spoken of as condensing by pressure reduction and is more or less effective without change in temperature, except such change as would naturally result from reduction in pressure. The conversion of the liquefiable constituents from the vapor state to the liquid state is increased by cooling the gas and particularly where cooling is coupled with pressure reduction. This invention contemplates cooling and pressure reduction within the retrograde range through the step of separating the liquids from the gas. While temperature reduction and pressure reduction alone will produce the recovery of liquids, tests have shown that by mixing a cold liquid with the gas for cooling the same, further recovery is accomplished because of such admixing. In view of the foregoing, it becomes obvious that liquefiable constituents may be recovered from high pressure gas flowing from the well at relatively high temperatures, in three modes or steps, as follows: by reducing pressure; by cooling; or by admixing a kindred liquid with the gas which is preferably cold or by a combination of any two or three of these steps.

A gas discharge pipe 21 leads from the top of the separator E and may include a pressure regulating valve 22 whereby a predetermined back pressure may be held on the separator, it being preferable to hold a pressure above 650 lbs. or within the retrograde condensation range. The gases to be separated will probably represent

from 85 to 95% of the original well stream and will readily separate and pass out through the pipe 21 at a pressure determined by the seating of the valve 22. Such gases may be referred to as "uncondensed" or "denuded" gases. Being recovered at a high pressure they may be marketed or used as is found profitable, or they may be returned to the ground under inexpensive compression.

10 The liquids which descend and collect in the lower portion of the separator E will carry with them a certain quantity of gas in solution, this quantity of gas in solution having been somewhat augmented by the previous injection of the denuded reflux into the well stream as will be hereinafter pointed out. The gas which remains in solution in the liquids recovered in the separator E will also depend somewhat upon the pressure at which the separation is made, but where separation is carried out at high pressures which are within the retrograde condensation range, there will always be in solution sufficient gas to enable the carrying out of the method of this invention. A liquid discharge pipe 23 extends from separator E and includes a float-controlled outlet valve 23. This pipe extends to a flash tank F and may include a pressure reducing valve 25. Usually the liquids will be discharged from the separator under a pressure in excess of 700 or 800 pounds and more frequently in excess of a thousand pounds, however, the invention is not to be limited to these figures. Assuming that the liquids were discharged under a pressure of 1,000 pounds and possibly at a temperature of 40 to 80 degrees, the pressure reducing valve 25 could be set to reduce the pressure to a degree anywhere below the retrograde condensation range. However, in order to get the best results the pressure should be reduced below 400 lbs. and possibly as low as 50 lbs. Very good results have been had where the pressure was reduced to around 100 lbs.

45 This sudden and amplified pressure reduction causes the release of the gas in solution and when the fluid flows into the tank F rapid expansion will take place, whereby the temperature of the liquid will be greatly reduced. By this pressure reducing or flashing step the temperature of the recovered liquids may be reduced to as low as 20° F. or even lower. The gas which is liberated or flashed off in the tank F is carried off through a pipe 26 which includes a pressure regulating valve 27, whereby the desired back pressure is held upon said tank. The amount of gas, as hereinbefore stated, which is discharged through the pipe 26 will be negligible when compared with the volume discharged through the pipe 21. In practically every location where a plant is established, suitable use will be found for the gas discharged from the pipe 26 and consequently will not be wasted; or it may be compressed and returned to the formation.

60 A pipe 28 leads from the flash tank and includes a float-operated valve 29, all of such valves herein illustrated preferably being of the diaphragm operated type so as to operate at various pressures, particularly where operation is required under high pressure. The recovered liquid which is discharged through the pipe 28 will be more or less stable because of the quantity of gas which has been flashed off. These liquids may be conducted to storage tanks or to any other point of disposal and will not require the usual weathering and will be substantially

free from the usual disturbances due to the presence of gas in solution, particularly the more volatile gases. Liquids recovered under this method will not suffer as much loss by evaporation and yet will contain enough high volatile constituents to make the product useful for the purpose for which it is recovered, such as a low grade motor fuel.

A pipe 30 leads from the flash tank F at a lower level than the pipe 28 and includes a valve 31. That portion of the recovered liquid or liquids which is discharged through the pipe 23 constitutes the reflux or liquefaction liquid. This reflux liquid, as before stated will have a low temperature which will depend somewhat upon preceding temperatures and pressures as well as the particular composition of the recovered liquid. Reflux liquid has been discharged from the flash tank at 20° F. but this degree is given merely as an example. This cold denuded reflux is conducted by the pipe 30 to a pump G where the pressure of the reflux is raised sufficiently for admixing it with the gas stream. While pumping may slightly raise the temperature, such a rise will be negligible. The pressurized reflux is discharged through a pipe 32 which connects with the pipes 14 and 16, as hereinbefore described.

This method provides a cold reflux without artificial or extraneous cooling at a low cost. Furthermore, the flashed reflux becomes a very excellent medium for absorbing or acquiring from the gas stream, large or small quantities of methane, ethane and small amounts of other valuable constituents which are in the vapor phase or are in solution with the liquids flowing with the gas stream. These gases when and as acquired, particularly under these high pressures, and when flashed to greatly reduced pressures, inherently cool the liquids from whence they are flashed; and this cooling is, therefore, in proportion in each case to the amount of reflux circulated and also in proportion to the pressure and presence of said gases in the agglomerated liquids. From this it follows that the amount of cooling desired may be controlled to some extent by the amount or quantity of denuded reflux which is circulated in the flow stream because of the temperature variation which results. This method provides a wide variation in temperature of the agglomerated flow stream, thus inherently providing cooling over a wide range of easy regulation.

It cannot be too strongly pointed out that temperature reduction plays a most important part in this recovery method and that the admixing of a liquefaction liquid augments the recovery which is proportionately due to cooling. Cooling causes condensation whereby liquefiable constituents are condensed. In some localities difficulty will be experienced with the formation of gas hydrates whereas in other fields there will be no hydrate trouble. The formation of hydrates, of course, depends upon the degree of temperature to which the gas stream is reduced and particularly upon the critical temperatures of the components of said stream. In many instances the dehydrator C will be adequate to remove water and prevent the formation of hydrates and in some cases even the dehydrator may be disposed of. If hydrates should occur there are many ways of taking care of the situation, one of which is exemplified in our copending application filed August 12, 1938, Serial No. 224,468.

In some localities where daily atmospheric

temperatures are not high it may be necessary to insulate the pipe lines, particularly those through which the stream flows after leaving the dehydrator C and better results may be obtained from insulating all pipe lines. It may be found advisable to bury the lines in the ground as well as to insulate them. This practice may be varied to suit conditions. It has been found that in some instances it is desirable to cool the reflux to a degree lower than can be obtained in the flash tank F.

Where a lower temperature is desired than can be obtained by flashing in the tank F, it has been found expedient to connect in the pipe 32 a heat exchanger or cooler H, as is shown in Figure 2, which may employ any suitable cooling means as cold water, cold gas, ammonia or the like. Such cooling will augment the cooling done in the flash tank and, of course, will not be as elaborate or nearly as expensive as where the entire cooling is done by artificial or extraneous means. Instead of using the cooler H it may be possible to use a colder heat exchange medium in the cooler B and cool the well stream to a lower degree at this point and to connect the dehydrator C in the pipe 10 in advance of the cooler B. Of course, where the cold reflux is introduced into the line 10 through the pipe 16 in advance of the cooler B the well stream will be cooled by such admixture. Further cooling will result where the pressure is reduced at the choke 15. It is pointed out that pressure reductions may take place at the valve 11 or in the tank D by reason of the choke 15 or in the separator E by reason of the valve 20 or at any one, two or three of these points. The arrangement is purposely made flexible in order to meet various conditions; however, this particular invention depends upon the flashing for cooling the reflux as its distinguishing feature.

What I claim and desire to secure by Letters Patent is:

1. The method of recovering desirable liquefiable constituents from a naturally gaseous well stream which initially flows at a high pressure and temperature within the retrograde condensation range of said constituents which includes, conducting a flowing stream under high pressure and relatively high temperature from a well, extracting free water from said stream to remove entrained moisture while said stream is still under high pressure, extracting hydrocarbon liquids from said stream and maintaining said stream under high pressure, rapidly dropping the pressure of the separated liquids from a high pressure within the retrograde range to a low pressure below said range to cool the liquids, carrying off a portion of the liquids as recovered liquids, separately carrying off the flash gas resulting from dropping the pressure of the separated liquids at a controlled pressure, and recirculating the remaining liquids in contact with said gaseous well stream as a liquefaction fluid.
2. The method of recovering desirable liquefiable constituents from a naturally gaseous well stream which initially flows at a high pressure and temperature within the retrograde condensation range of said constituents which includes, conducting a flowing stream under high pressure and relatively high temperature from a well, admixing the stream with large quantities of a liquefaction liquid which has been precooled to a low temperature at which maximum agglomeration of the liquefiable fractions in said stream may be accomplished and below the critical de-

gree at which gas hydrates are formed, extracting the free hydrocarbon liquids from said stream at a temperature below that at which gas hydrates form and maintaining said stream under high pressure, rapidly dropping the pressure of the separated liquids from a high pressure within the retrograde range to a low pressure below said range to cool the liquids, separating and carrying off flash gas resulting from dropping the pressure of the separated liquid at a controlled pressure, carrying off a portion of the liquids as recovered liquids, and recirculating the remaining liquids as the liquefaction fluid.

3. The method of recovering desirable liquefiable constituents from a naturally gaseous well stream which initially flows at a high pressure and temperature within the retrograde condensation range of said constituents which includes, conducting a flowing stream under high pressure and relatively high temperature from a well, admixing the stream with a liquefaction liquid at a minimum temperature at which maximum agglomeration of liquefiable fractions may be accomplished and at a degree Fahrenheit below the critical degree at which gas hydrates are formed, whereby maximum recovery of hydrocarbon liquids may be effected, extracting hydrocarbon liquids from said stream, maintaining said stream under high pressure, rapidly dropping the pressure of the separated liquids from a pressure in excess of 600 pounds to less than 150 pounds, whereby the gas in solution is quickly released and the temperature of the liquids is reduced to a degree Fahrenheit below the freezing point of water, separately carrying off the released gas at a controlled pressure below 150 pounds, and recirculating a portion of said liquid as the liquefaction medium.

4. The method of recovering desirable liquefiable constituents from a naturally gaseous well stream which initially flows at a high pressure and temperature within the retrograde condensation range of said constituents which includes, conducting a flowing stream under high pressure and relatively high temperature from a well, admixing the stream with a liquefaction liquid at a minimum temperature at which maximum agglomeration of liquefiable fractions may be accomplished and at a degree Fahrenheit below the critical degree at which gas hydrates are formed, whereby maximum recovery of hydrocarbon liquids may be effected, extracting hydrocarbon liquids from said stream, maintaining said stream under high pressure, rapidly dropping the pressure of the separated liquids from a pressure in excess of 600 pounds to less than 150, whereby the gas in solution is quickly released and the temperature of the liquids is reduced to a degree Fahrenheit below the freezing point of water, separately carrying off the released gas at a controlled pressure below 150 pounds, carrying off a portion of the cold liquids as a liquefaction liquid, raising the pressure of the cold liquefaction liquid to above that of the

flowing stream, and introducing the repressured cold liquefaction liquid into the said stream as the liquefaction liquid.

5. The method of recovering desirable liquefiable constituents from a naturally gaseous well stream which initially flows at a high pressure and temperature within the retrograde condensation range of said constituents which includes, conducting a flowing stream under high pressure and relatively high temperature from a well, extracting the free hydrocarbon liquids from said stream and maintaining said stream under high pressure, rapidly dropping the pressure of the separated liquids from a high pressure to a low pressure to denude the liquids of gas, separately carrying off the flash gas resulting from dropping the pressure of the separated liquids at a controlled pressure, carrying off a portion of the liquids to storage, and recirculating and injecting the remaining denuded cool liquids into the well stream, whereby liquefiable fractions in the well stream are precipitated as liquids and said denuded liquefaction medium more readily absorbs gaseous products from said stream and holds them in solution.

25 6. The method of recovering desirable liquefiable constituents from a natural gaseous stream which initially flows at a high pressure and temperature within the retrograde condensation range of said constituents which includes, cooling said stream, separating uncondensed gas from the condensed liquids of the stream at a high pressure within the retrograde condensation range of the said constituents, rapidly reducing the pressure from said retrograde range to a low pressure below said range to cool the liquids, separately carrying off the flash gas resulting from dropping the pressure of the separated liquids at a controlled pressure, carrying off a portion of the cooled liquids, and recirculating said portion of the cooled liquids in the gaseous stream to cool the same and to condense and recover liquefiable constituents therefrom.

45 7. The method of recovering desirable liquefiable constituents from a natural gaseous stream which initially flows at a high pressure and temperature within the retrograde condensation range of said constituents which includes, cooling said stream, separating uncondensed gas from the condensed liquids of the stream at a high pressure within the retrograde condensation range of the said constituents, rapidly reducing the pressure from said retrograde range to a low pressure below said range to cool the liquids, separately carrying off the flash gas resulting from dropping the pressure of the separated liquids at a controlled pressure, carrying off a portion of the cooled liquids, further cooling the portion of said liquids which is carried off, and recirculating said portion of the cooled liquids in the gaseous stream to cool the same and to condense and recover liquefiable constituents therefrom.

JAY P. WALKER.
